UNITED STATES PATENT OFFICE.

MILES P. SHOUP, OF SPRINGDALE, PENNSYLVANIA, ASSIGNOR OF ONE-FOURTH TO
JAMES W. JOHNSTON, OF SPRINGDALE, PENNSYLVANIA.

COLLAPSIBLE DERRICK.

1,084,043.

Specification of Letters Patent.

Patented Jan. 13, 1914.

Application filed February 10, 1913. Serial No. 747,580.

To all whom it may concern:

Be it known that I, MILES P. SHOUP, a citizen of the United States, and resident of Springdale, in the county of Allegheny and State of Pennsylvania, have invented a new and useful Improvement in Collapsible Derricks; and I do hereby declare the following to be a full, clear, and exact description thereof.

10 My invention relates to collapsible derricks.

The object of my invention is to provide such a derrick which is adaptable for use in connection with buildings where there is 15 a porch or other projecting structure extending out from the building, and to provide means for bridging over the space from the piano or other object lifted to the window under such conditions, so that the piano 20 may be moved into the window or doorway with a minimum expenditure of time and labor.

To these ends my invention comprises the novel features hereinafter set forth and 25 claimed.

In the drawing Figure 1 is a view of my improved derrick erected in front of the building and showing the piano elevated thereby. Fig. 2 is a vertical sectional view 30 showing the piano raised and the platform or skid shown in dotted lines in position to sustain the piano while it is being moved into the window; and Fig. 3 is a longitudinal sectional view showing the derrick when 35 in collapsed condition.

Referring to the drawing, the numeral 2 designates the lowermost section which is made up of pipe of suitable diameter, the lower ends of the pipes being threaded and 40 connected to the T-connections 3 which form the feet of the derrick, and the lower halves of said T-connections are filled up with wood 4, or other suitable material. A rod 5 connects the T-connections 3 and forms 45 a brace at the lower end of the derrick.

Telescoping within the lower section 2 of the derrick is the intermediate section 6 formed of pipe of such diameter as will fit neatly within the pipes of the lower section, so as to slide up and down therein. The sections 2 and 6 are perforated as at 7 so that when the derrick is elongated the perforations 7 will register with each other and the pins 8 are then introduced as shown

in Fig. 1 to hold the parts in this extended 55 position.

The third section 9 is illustrated which fits within the section 6 and likewise is connected with the section 6 by pins 10 when the derrick is extended as indicated in Fig. 1. 60

It is apparent that any suitable number of sections may be employed according to the height to which it is desired to extend the derrick. The uppermost section 9 has the T-connections 11 at the upper ends and the 65 rod 12 connects said T-connections and forms the support for the main pulley-block 13. This cross-bar 12 also forms the support for the pulleys 14. Cables 15 pass over the pulleys 14 and said cables are connected with 70 the outer ends of the movable bar 16 which engages the guides 17 on the lower face of the platform or skid 18. This platform 18 may be made of wood or any suitable material and adjacent to the inner end is the 75 cross beam 19. When the platform 18 is in the position shown in full lines Figs. 1 and 2, it is suspended by the bar 16 engaging the ends of the guide 17 and is held in a vertical position. The cable 20 is connected to 80 the upper or inner end of the platform 18 and said cable is adapted to pass up and into the window 21 through which the piano 22 or other article of furniture is to be admitted to the house or apartment. 85

When the derrick is to be erected, the sections are first drawn out and connected by the pins 8 and 10 whereupon the derrick is raised, and, by means of the guy lines 23 which are secured to any post or convenient 90 support along the side-walk, the derrick is thus held securely in its vertical position. The piano is then connected to the lifting cable 24 and by means of this cable is elevated until it is opposite the window 21 as 95 shown in Fig. 2. The piano is supported in this position until the operators by pulling on the cables 15 raise the platform 18, and, when the platform has been raised in this manner to the proper height, the operator 100 at the window by means of the cable 20 tilts the platform until it is brought around into a horizontal position with the inner end resting upon the sill of the window and the cross beam 19 abutting against the outer 105 edge of the sill, so as to prevent the further inward movement of the platform. The cables 15 are then wrapped around the pins 26

at the lower end of the derrick and the platform 18 is held securely in the position indicated in dotted lines in Fig. 2. The operators then ease up on the cable 24 supporting the piano until it is lowered onto the platform 18 and it is then a simple matter to move the piano along the platform or skid 18 into the window 21. Having disposed of the piano in this way, it is a simple matter 10 to lower the platform 18, release the guy-lines 23, and pins 8 and 10, whereupon the sections of the derrick are moved into each other so as to bring the derrick into the compact form indicated in Fig. 3 when it 15 may be readily loaded onto the wagon or moving van.

The operation of lifting a piano and introducing it into the second or third story or even to a higher level is accomplished 20 with ease and in a very short time without liability to accident due to the falling of the piano, and furthermore by the use of the platform 18 the derrick may be set up in front of a porch or other projecting portion 25 of a building and the space between the derrick and window bridged by the platform 18, so that no difficulty in moving the piano over such a distance from the building into the window is encountered.

30 The device is simple in construction and the parts are not liable to get out of order. Furthermore the derrick can be erected and the piano or other article moved into the building without liability of defacing the 35 building in any way due to the piano swinging in toward the building and defacing the exterior thereof or the framework of the window through which it is admitted.

What I claim is:

40 1. The combination of a derrick, means for lifting the object to be raised, a transverse bar suspended therefrom, means car-

ried by the derrick for raising said bar, and a platform carried by said bar longitudinally movable and tilttable thereon.

45

2. The combination of a derrick, means for lifting the object to be raised, a transverse bar suspended from said derrick, means supported by the derrick for raising said bar, a platform, and a guide on said 50 platform with which said bar engages, said platform being longitudinally movable and tilttable on said bar.

3. The combination of a derrick, means for lifting the object to be raised, pulleys 55 on said derrick, a transverse bar, cables connected to opposite ends of said bar and passing over said pulleys, a platform, and a guide on said platform with which said bar engages, said platform being longitudinally 60 movable and tilttable on said bar.

4. The combination of a derrick, means for lifting the object to be raised, a transverse bar suspended from said derrick, means carried by said derrick for raising said bar, 65 a platform, a guide on said platform engaged by said bar, said platform being longitudinally movable and tilttable on said bar and a cable connected to one end of said platform.

70

5. The combination of a derrick, means for lifting the object to be raised, a transverse bar suspended from said derrick, means carried by the derrick for raising said bar, a platform, and a guide on the lower face of 75 said platform engaged by said bar, said platform being longitudinally movable and tilttable on said bar.

In testimony whereof, I the said MILES P. SHOUP have hereunto set my hand.

MILES P. SHOUP.
